UNITED STATES PATENT OFFICE.

GUNNER JULIUS JOHANNES ROSENDALH, OF NEWCASTLE-ON-TYNE, ENGLAND.

MEANS FOR PRODUCING A PERFORATED TAPE BY ELECTRIC-CURRENT IMPULSES.

Application filed April 10, 1922. Serial No. 551,280.

To all whom it may concern:

Be it known that I, GUNNER JULIUS JOHANNES ROSENDALH, of Gosforth, Newcastle-on-Tyne, England, a subject of the 5 King of Denmark, have invented certain new and useful Improvements in or Relating to Means for Producing a Perforated Tape by Electric-Current Impulses, of which the following is a specification.

10 The invention relates to telegraphic receiving apparatus of the kind employed particularly in the Wheatstone Morse system and adapted to produce by means of signal currents transmitted to the line, a 15 perforated tape which is a duplicate of that used at the transmitting station, said tape being fed step-wise positively by a feed wheel synchronously with the punching of the tape, and wherein two electric current 20 impulses are required for the production of a signal, namely a positive and a negative one, these impulses energizing electro-magnetic devices which in turn control the actuation of the punches and the feed of 25 the tape.

According to the Wheatstone system two current impulses are required, for instance a positive one and a subsequent negative one or vice versa, for the formation of a 30 signal, but the present invention is applicable not only to the Wheatstone system but also to other systems using signal currents which are transmitted at intervals of time having a certain constant value or 35 a multiple thereof.

The object of the present invention is to provide a simple and reliable apparatus of this character, the design also providing for complete accessibility of the parts for 40 pairs and renewal.

The apparatus according to the invention is chiefly characterized by the fact that the actuation of the punches and the feeding of the tape is controlled by friction clutches 45 mounted in series on a continuously rotating shaft, two of said clutches serving to operate each punch and one being controlled by an electro-magnetic device energized by the positive impulses, and the 50 other by a similar device energized by the negative impulses, in such manner that they are rendered operative upon energization of the appurtenant electro-magnetic device. A third clutch is adapted 55 to control the feed of the tape, this clutch normally operating the tape feed mecha-

nism and being so operatively connected to the adjacent aforesaid pair of recording clutches that it is stopped to effect discontinuation of the tape feed during 60 the punching of the tape.

An embodiment of the invention is illustrated in the accompanying drawings in which:—

Fig. 1 is a sectional end view of the apparatus on the line A—A of Fig. 2.

Fig. 2 is a plan view of the apparatus.

Fig. 3 is a sectional detail view on the line B—B of Fig. 2 showing mainly one 70 of the punching devices.

Fig. 4 is a side elevation of the apparatus, the mechanism for punching and feeding the ribbon being removed and

Fig. 5 shows a portion of a perforated 75 tape.

Referring to the drawings, 1 designates the main shaft suitably supported at the ends by bearings 2, 2 and on which are mounted in series the three clutches 3, 4 and 5, the clutch members 3 and 4 being 80 adapted to control the recording of the negative and positive impulses respectively, that is to say, the clutch member 3 controls the punching of one row of holes in the tape and the other clutch member 4 the punching of the other row of holes on the opposite side of the centre line of the tape which is provided with equidistant feed holes while the third clutch 5 serves to control the feed of the tape.

The clutch member 3 consists of a spiral spring 6 wound on the shaft 1, one end of said spring having secured thereto or integral therewith an abutment or projection 7, and the other end being provided with two adjacent cams 8, 9 which are relatively offset. The second clutch member 4 is identical in construction and operation with the member 5 having adjacent cams 8^a, 9^a and an abutment 7^a, but the cams are advanced 95 to the extent of 180° with respect to the cams 8, 9, and the convolutions and position of the cams are reversed so that the cams of the two clutches are adjacent and the abutments remote from each other. The third clutch 5 is similar to the clutches 3, 4 having an abutment 7^b but only one cam 12. The action of these clutches is that on account of the friction between the spring and shaft, the clutches will normally rotate 100 with the shaft until a stop or detent is brought into engagement with the abut-

ment, this causing the tension of the coils to be released with consequent stoppage of the clutch on its shaft. Inversely, an obstruction against rotation applied to the 5 other end of the spring will tend to tighten the clutch on its shaft.

The abutment 7 on the clutch 3 is normally engaged by one end of a detent 13 pivoted at 13^a and carrying at the other 10 end an armature 15 actuated by an electromagnet 17 which is energized by the negative signal impulses, and the abutment 7^a of the other recording clutch 4 is similarly engaged by a detent 14 carrying an armature 16 actuated by an electromagnet 18 energized by the positive signal impulses. The detents are under the influence of springs 13^b tending to hold them in engaging position. The cams 8, 8^a on the 15 clutches 3, 4 are designed to each actuate a double armed rocker 20, 21 each fixed on a separate spindle 55, 55^a carried by bracket 53 and each of said rockers serving to actuate a punch for perforating the tape, 20 one arm 20^a of each rocker (Fig. 3) having detachably connected to it a punch 23, 24 working in bores in the bracket 53, the tape being fed by means of a conventional form of feed-wheel 28 which engages feed 25 perforations disposed centrally along the tape. 51 designates the tape which passes in front of the punches between two die plates 54 and the face of the bracket 53, and thence onto the feed wheel 28. 30

35 It will be seen that the cams 8, 8^a acting on the arms 20^a, 20^b of the rockers will produce the desired reciprocating movement of the punch, one revolution of the shaft 1 causing the punch to punch the 40 tape once.

The other cams 9, 9^a both co-operate with and are adapted to move a lever 30 pivoted at 36 into engagement with the abutment 7^b of the feed-clutch 5 with a view to stopping the latter and thus stopping the feed of the tape during the punching operation. The cam 12 on said feed clutch operates a double armed rocker 31 pivoted at 32 and carrying a spring influenced pawl 33 which 45 coacts with a ratchet wheel 34 fixed to the spindle 35 carrying the feed wheel 28. An adjustable stop 60 is provided to ensure the ratchet wheel being rotated to the extent of one tooth only at a time, i. e. the tape is 50 fed forward to the extent of one feed perforation at each revolution of the shaft 1.

The lever 30 engages at one end the cams 9, 9^a, (Fig. 4) and is adapted to be rocked by one of said cams, in the case of a dash, or 55 both simultaneously in the case of a dot as the case may be, this end of the arm being held in engagement with both cams 9, 9^a by a spring 37 housed in a bracket 38; the other end of the lever 30 engages in a 60 slot in a detent 39 slidably mounted in a

bracket 40 and normally disengaged from the abutment 7^b but adapted to be engaged therewith during rotation of either of the cams 9, 9^a prior to and during the punching of the tape.

In operation the shaft 1 is driven at a speed slightly higher than that of the corresponding shaft of the transmitting apparatus in order to allow the clutches to return to their starting point before the next signal arrives. The clutch 5 during such rotation of the shaft rotates with the latter and consequently the feed-wheel 28 for the tape is driven by cam 12 through the members 31, 33, 34, 35. The recording clutches 3, 4 are normally held stationary by engagement of their abutments 7, 7^a by the relative detents 13, 14, but upon one of the electromagnets 17, 18 being energized by an electric impulse through a condenser in the circuit the corresponding armature 15 is attracted and thus the detent retracted so that the corresponding recording clutch is released and immediately rotates with the shaft. The electro-magnets energize by means of a keyboard, not shown, or they may energize by some means positioned at a considerable distance from the machine depending upon the circumstances.

In due course the lever 30 controlling the feed-clutch 5 is rocked by the corresponding cam 9 or 9^a of the recording clutch, whereby the detent 39 is engaged with the abutment 7^b so that the feed-clutch 5 is held stationary and consequently the feed of the tape is discontinued. The appurtenant punch-actuating lever 20 or 21 is then operated by the corresponding cam 8 or 8^a of the recording clutch whereby the punch is caused to perforate the tape and is then 105 returned to its original position, the detent being returned to re-engage the controlling clutch simultaneously with the punching operation. As soon as the punching operation is finished the feed-clutch 5 is released 110 by its controlling lever 30 so that the feed of the tape is continued.

Fig. 5 illustrates a section of tape of the kind employed in the machine, this tape having a central row of feed perforations 115 62 with which the feed wheel 28 engages. This section of tape is shown by way of example as having been punched with a dot and dash signal representing the letter "a". The punched holes 63, 64 represent as usual 120 the dot and the holes 65, 66 the dash, the holes 63, 65 being produced by a subsequent positive and negative impulse, whereupon the paper is fed forward and the subsequent positive impulse causes the hole 64 125 to be punched, the tape is then fed forward again and the hole 66 is punched upon the arrival of the negative impulse.

In order to provide for the positive return of the detents 13, 14 to their original posi- 130

tion for engaging the abutments 7, 7^a after each revolution, independently of the spring 13^b, there is mounted on each of the spindles 55, 55^a an arm 57 disposed above the detaining ends of the detents 13, 14. During rotation of the clutches 3 or 4, as the case may be, the corresponding arm 57 will be caused to descend due to the spindle on which it is mounted being turned by one of the rockers 20, 21, so that the detent will be pressed down by the arm to the original detaining position shown, ready to engage the abutment 7 or 7^a. To prevent breakage of the mechanism due to possible incorrect co-action of the arms 57 with their detents, the arms are yieldingly mounted as by mounting them loosely on their spindles but pressing them laterally by spring 59 into frictional engagement with bushes fixed to the spindle. The arms 57 may be adjusted for angularity on their spindles by means of superimposed adjustment screws 58 supported by the bracket 53.

Finally, it will be obvious that a quite similar system may be used in the so-called reversal system, in which, for instance, a positive current impulse produces a dot and a negative current a dash. Also the apparatus is obviously applicable to systems in which there are a plurality of rows of holes above each other in the paper tape.

What I claim as my invention and desire to secure by Letters Patent of the United States is:—

1. In a device of the character described the combination of punches adapted to produce series of perforations in an associated tape, a continuously rotating shaft, two clutches mounted in series on said shaft, an electromagnetic device energized by impulses of one polarity adapted to control one of said clutches, a second electro-magnetic device energized by impulses of opposite polarity adapted to control the other clutch, means for normally restraining said clutches against rotation with the shaft, means for rendering the clutches operative to rotate with said shaft upon energization of the respective electro-magnetic device, tape feeding means, a third clutch also mounted on said shaft for controlling said tape feeding means, means for normally connecting said clutch operatively with the shaft to feed the tape and means for stopping said feed during the operation of the first two mentioned clutches.

2. In a device of the character described the combination with a punch adapted to produce perforations in an associated tape, a continuously rotating shaft, a clutch mounted on said shaft, and an electro-magnetic device adapted to control the operation of said clutch on energization by electric impulses, said clutch comprising a spring

wound on the shaft and tending to rotate therewith, an abutment carried by one end of said spring, a cam carried by the opposite end of said spring and adapted to operate the punch, and a detent normally engaging said abutment and adapted to be operated by the electro-magnetic device.

3. In a device of the character described, the combination of punches adapted to produce series of perforations in an associated tape, a continuously rotating shaft, two clutches mounted in series on said shaft, an electro-magnetic device energized by positive impulses adapted to control one of said clutches and a second electro-magnetic device energized by negative impulses adapted to control the other clutch, each of the aforesaid clutches comprising a spring wound on the shaft and tending to rotate therewith, a cam at one end of the spring adapted to operate a punch, an abutment at the other end of the spring, a detent normally engaging said abutment to hold the clutch stationary, but adapted to be actuated by the respective electro-magnetic device on its energization, to cause the clutch to grip the shaft and rotate therewith, whereby the cam actuates the punch.

4. In a device of the character described the combination of punches adapted to produce series of perforations in an associated tape, a continuously rotating shaft, two clutches mounted in series on said shaft, an electro-magnetic device energized by impulses of one polarity adapted to control one of said clutches, a second electro-magnetic device energized by impulses of opposite polarity adapted to control the other clutch, means for normally restraining said clutches against rotation with the shaft, means for rendering the clutches operative to rotate with said shaft upon energization of the respective electro-magnetic device, tape feeding means and a third clutch also mounted on said shaft for controlling said tape feeding means, said third clutch comprising a spring wound on the shaft, an abutment carried by one end of said spring, a cam carried by the other end of said spring serving to actuate the tape feeding means, and means operated by the two first mentioned clutches for periodically engaging said abutment to stop said third clutch and thereby the feed of the tape during the tape punching operation, and to release said clutch for actuation of the tape feeding means at other times.

In witness whereof I have signed this specification in the presence of two witnesses.

GUNNER JULIUS JOHANNES ROSENDAHL.
